UNITED STATES PATENT OFFICE.

DAVID HINDAHL, OF CHICAGO, ILLINOIS, ASSIGNOR TO NATIONAL DUMP CAR COMPANY, OF CHICAGO, ILLINOIS, A CORPORATION OF MAINE.

OPERATING MECHANISM FOR DUMP CARS.

Application filed June 5, 1924. Serial No. 717,996.

The present invention relates to operating mechanism for dump cars.

More particularly the present invention relates to means for controlling the dump doors of railway dump cars.

In certain common types of dump cars the dump doors are designed to open suddenly upon the releasing of certain mechanism. In certain well known types of car said releasing mechanism includes flexible connectors which under certain conditions hang in loops below the car body. Difficulty has been encountered in the past due to the fact that said hanging flexible connectors are likely to get out of cooperative relationship with the other parts of the releasing mechanism, requiring personal attention on the part of the operators of the car.

An object of the present invention is to provide operating mechanism for the doors of railway dump cars, which mechanism will have a minimum of likelihood to get out of order.

A further object is to provide railway dumping mechanism of the type employing flexible connectors, which mechanism will effectually prevent said flexible connectors from swinging out of operative positions.

Further objects will appear as the description proceeds.

Referring to the drawings—

Figure 1 is a sectional view taken transversely of a dump car of the center dumping type;

Figure 2 is a view taken in the direction indicated by the arrows 2—2 of Figure 1; and

Figures 3 and 4 are fragmentary views illustrating in top plan and side elevation, respectively, certain parts of operating mechanism embodying the principles of the present invention.

The numerals 10—10 indicate the sides of the car, while the numerals 11—11 indicate the center sills of said car. Mounted transversely of the car is the operating shaft 12 which carries two chains 13 and 14 for operating the hopper doors 15 and 16, which are pivoted along the longitudinal axes 17 and 18, respectively, said doors being shown in closed position in Figure 1.

Pivoted connected to the doors 16 by means of the pivot pin 16' located in an axis

distant from the pivotal axis 18 is the link 19, which may take the angular form shown 55 in the drawing for a purpose to be referred to hereinafter. Pivoted connected to the door 15 on the shaft 20, located on an axis distant from the pivotal axis 17, is the crank 21, which crank is pivotally connected 60 to the link 19 by means of the pivot pin 22.

Said crank 21 may consist of three parallel plates 23, 24 and 25, best illustrated in Figure 3. The link 19 may be connected to the pivot pin 22 between the plates 23 and 65 24.

Mounted upon the shaft 20 is the link 26, said link being adapted to have rotative movement relative to the shaft 20. Said link 26 is sufficiently elongated to underlie 70 the pivot pin 22 and is provided at its outer end with an eye for receiving the chain 13. The link 26 may be provided with the boss 26' lying between and abutting against the plates 24 and 25. By reason of the engagement of the boss 26' with the plates 24 and 25, the outer end of the link 26 will be secured against swinging or creeping movement longitudinally of the car. By reason of this construction, therefore, the chain 13 80 even when hanging loose will not tend to get out of cooperative relationship with the pivot pin 22. The other end of the chain 13 is connected to the shaft 12 at the point 27. It will be clear that when the chain 13 85 is wound up upon the shaft 12, it will raise the link 26 to lift the pivot pin 22 for a purpose to be referred to hereinafter.

Connected to the crank 21 at a point adjacent to the shaft 20 is the link 28, which 90 constitutes part of the chain 14. In part of its travel the chain 14 raises the shaft 20, and for this reason said shaft 20 may be provided with a flanged sheave portion 29 for engaging the chain 14. The link 19 is 95 provided with a sheave 30, which sheave engages the chain 14. A guard plate 31 may be provided to keep the chain 14 in operative relationship with the sheave 30. The other end of the chain 14 may be secured to the 100 shaft 12 at the point 32.

The parts are so designed that when the dump doors 15 and 16 are in closed position the chain 14 will have a greater number of convolutions upon the shaft 12 than has 105 the chain 13. According to the illustrated

- embodiment of the present invention, the chain 13 has two convolutions upon the shaft 12, while the chain 14 has four convolutions upon said shaft. In the position referred to, that is, with the doors closed, the link 19 will rest upon the crank 21 and the pivot pin 22 which pivotally connects the link 19 and crank 21 will lie in a position past dead center, whereby stresses applied to the doors 15 and 16 to urge same to open position will react upon link 19 and crank 21 with a toggle action to force pivot pins 16' and 20 toward one another, whereby to hold said doors 15 and 16 in closed position.
- 15 When the pivot pin 22 is raised past dead center with reference to the pivot pins 20 and 16', the doors 15 and 16 will fly open, resulting in the practically instantaneous dumping of the car.
- 20 With the doors in closed position, as indicated in Figure 1, releasing may be accomplished by turning the shaft 12 in the direction indicated by the arrow in Figure 1. Such motion will result in the unwrapping 25 of the chains 13 and 14 from the shaft 12. After the chain 13 has been completely unwrapped from the shaft 12, a further revolution of shaft 12 in the direction indicated by the arrow will cause the chain 13 to again 30 wrap itself upon shaft 12, but in the reverse direction from that indicated in the drawing.

The wrapping up of chain 13 on the shaft 12 will raise link 26 to a position in which 35 said link 26 will lift the pivot pin 22 to a position past dead center. At this time the chain 14 will have become practically unwrapped from the shaft 12. The raising 40 of pivot pin 22 above its dead center will cause the doors 15 and 16 to fly open, resulting in the instantaneous dumping of the car, whereby the releasing mechanism will assume the positions indicated in broken lines in Figure 1.

45 A more complete description of the winding operation is not necessary in the present application, reference for this purpose being made to the patent to Neikirk No. 1,497,931, which also describes means for ensuring safety to the operator in case the chains 13 and 14 should not be properly proportioned.

The link 26 will, for all practical purposes, hold its position in a direction longitudinally of the car, so that when the shaft 12 is again rotated to wind up the chains 13 and 14 to the positions shown in Figures 1 and 2, the chain will always be in cooperative relationship with the pivot pin 22, whereby difficulties due to the swaying of the chains will be minimized.

Although a preferred embodiment of the present invention has been chosen for illustration, it is clear that many modifications will occur to those skilled in the art,

and it is intended to cover all such modifications that fall within the scope of the appended claims.

What is claimed is:

1. Dump car construction comprising dump doors, trip mechanism including a pivotally mounted lever for holding said doors closed or for causing the sudden release of said doors under load, a flexible connector for operating said trip mechanism, and a relatively rigid member held against movement longitudinally of said car for holding said chain in operative relationship with said trip mechanism, said rigid member being pivotally mounted upon the pivotal connection of said lever. 70
2. Dump car construction comprising dump doors, trip mechanism including a pivotally mounted lever for holding said doors in closed position and for causing the sudden release of said doors under load, means for moving said trip mechanism for door releasing functions consisting of a shaft, a flexible connector connected to be operated by said shaft, and a member held against movement longitudinally of said car for operating said mechanism, said flexible connector being connected to said last mentioned member, said member being pivotally mounted upon the pivotal connection of said lever. 75
3. A dump car comprising a pair of dump doors adapted to control dumping between the tracks upon which said car is mounted, means operating with a toggle action to hold said doors in closed position under the influence of weight operative upon said doors, said means comprising levers pivotally secured to said doors and to each other and an operating member for controlling the relative positions of the pivotal connections of said levers, said operating member including a rigid member and a flexible chain, said rigid member being pivotally mounted upon the pivotal connection of one of said levers and having cooperative relationship with the pivotal connection between said levers. 80
4. A dump car comprising a pair of dump doors adapted to control dumping between the tracks upon which said car is mounted, means operating with a toggle action to hold said doors in closed position under the influence of weight operative upon said doors, said means comprising levers pivotally secured to said doors and to each other and an operating member for controlling the relative positions of the pivotal connections of said levers, said operating member including a rigid member and a flexible chain, said rigid member being pivotally mounted upon the pivotal connection of one of said levers and having cooperative relationship with the pivotal connection between said levers. 85
5. A dump car comprising a pair of dump doors adapted to control dumping between the tracks upon which said car is mounted, means operating with a toggle action to hold said doors in closed position under the influence of weight operative upon said doors, said means comprising levers pivotally secured to said doors and to each other and an operating member for controlling the relative positions of the pivotal connections of said levers, said operating member including a rigid member and a flexible chain, said rigid member being pivotally mounted upon the pivotal connection of one of said levers and having cooperative relationship with the pivotal connection between said levers. 90
6. A dump car comprising a pair of dump doors adapted to control dumping between the tracks upon which said car is mounted, means operating with a toggle action to hold said doors in closed position under the influence of weight operative upon said doors, said means comprising levers pivotally secured to said doors and to each other and an operating member for controlling the relative positions of the pivotal connections of said levers, said operating member including a rigid member and a flexible chain, said rigid member being pivotally mounted upon the pivotal connection of one of said levers and having cooperative relationship with the pivotal connection between said levers. 95
7. A dump car comprising a pair of dump doors adapted to control dumping between the tracks upon which said car is mounted, means operating with a toggle action to hold said doors in closed position under the influence of weight operative upon said doors, said means comprising levers pivotally secured to said doors and to each other and an operating member for controlling the relative positions of the pivotal connections of said levers, said operating member including a rigid member and a flexible chain, said rigid member being pivotally mounted upon the pivotal connection of one of said levers and having cooperative relationship with the pivotal connection between said levers. 100
8. A dump car comprising a pair of dump doors adapted to control dumping between the tracks upon which said car is mounted, means operating with a toggle action to hold said doors in closed position under the influence of weight operative upon said doors, said means comprising levers pivotally secured to said doors and to each other and an operating member for controlling the relative positions of the pivotal connections of said levers, said operating member including a rigid member and a flexible chain, said rigid member being pivotally mounted upon the pivotal connection of one of said levers and having cooperative relationship with the pivotal connection between said levers. 105
9. A dump car comprising a pair of dump doors adapted to control dumping between the tracks upon which said car is mounted, means operating with a toggle action to hold said doors in closed position under the influence of weight operative upon said doors, said means comprising levers pivotally secured to said doors and to each other and an operating member for controlling the relative positions of the pivotal connections of said levers, said operating member including a rigid member and a flexible chain, said rigid member being pivotally mounted upon the pivotal connection of one of said levers and having cooperative relationship with the pivotal connection between said levers. 110
10. A dump car comprising a pair of dump doors adapted to control dumping between the tracks upon which said car is mounted, means operating with a toggle action to hold said doors in closed position under the influence of weight operative upon said doors, said means comprising levers pivotally secured to said doors and to each other and an operating member for controlling the relative positions of the pivotal connections of said levers, said operating member including a rigid member and a flexible chain, said rigid member being pivotally mounted upon the pivotal connection of one of said levers and having cooperative relationship with the pivotal connection between said levers. 115
11. A dump car comprising a pair of dump doors adapted to control dumping between the tracks upon which said car is mounted, means operating with a toggle action to hold said doors in closed position under the influence of weight operative upon said doors, said means comprising levers pivotally secured to said doors and to each other and an operating member for controlling the relative positions of the pivotal connections of said levers, said operating member including a rigid member and a flexible chain, said rigid member being pivotally mounted upon the pivotal connection of one of said levers and having cooperative relationship with the pivotal connection between said levers. 120
12. A dump car comprising a pair of dump doors adapted to control dumping between the tracks upon which said car is mounted, means operating with a toggle action to hold said doors in closed position under the influence of weight operative upon said doors, said means comprising levers pivotally secured to said doors and to each other and an operating member for controlling the relative positions of the pivotal connections of said levers, said operating member including a rigid member and a flexible chain, said rigid member being pivotally mounted upon the pivotal connection of one of said levers and having cooperative relationship with the pivotal connection between said levers. 125
13. A dump car comprising a pair of dump doors adapted to control dumping between the tracks upon which said car is mounted, means operating with a toggle action to hold said doors in closed position under the influence of weight operative upon said doors, said means comprising levers pivotally secured to said doors and to each other and an operating member for controlling the relative positions of the pivotal connections of said levers, said operating member including a rigid member and a flexible chain, said rigid member being pivotally mounted upon the pivotal connection of one of said levers and having cooperative relationship with the pivotal connection between said levers. 130

swinging end out of cooperative relationship with said levers.

5. A railway dump car comprising dump doors for controlling dumping between the tracks upon which said car is mounted, means for holding said doors closed, said means comprising toggle levers, said levers being pivotally connected to said doors and to one another, means for controlling the toggle action of said levers, said means comprising a rigid member pivoted to one of said doors at the point of pivotal connection of one of said levers and having a portion for controlling the relative positions of the connections of said levers to said doors and to one another, and a flexible member for controlling the position of said rigid member.

6. A railway dump car comprising dump doors for controlling center dumping, toggle levers for holding said doors closed, pivotal means for connecting said levers together and for connecting one of said levers to each of said doors, a rigid member pivotally mounted upon one of said pivotal means, means for preventing swinging movement of said rigid member except about the axis of its corresponding pivotal means, said rigid member having a portion cooperating with the pivotal connection between said levers, and a flexible member for controlling the position of said rigid member.

Signed at Chicago, Illinois, this 2nd day of June, 1924.

DAVID HINDAHL.
